UNITED STATES PATENT OFFICE.

JAMES LEONADUS RESPESS AND ARTHUR MAZYCK, OF COLUMBIA, SOUTH CAROLINA.

TAG.

Application filed April 28, 1924. Serial No. 709,607.

This invention relates to tags and more particularly to tags for use on cotton bales and like articles where it is desirable to keep a record of the various facts concerning a bale from the time of its arrival, to the time of its departure, from any particular place.

It is an object of this invention to provide a tag of the class described which will 10 be provided with a number of separable parts in order that records may be kept on these parts as desired.

It is a further object of this invention to provide a tag having two ends, each of which 15 may be attached to a bale, with a line of perforations between the two parts.

It is still another object of this invention to provide in a tag of the type described a portion to be initially attached to a bale, a 20 portion to be finally attached to a bale to indicate the completion of a sequence of operations, and a plurality of detachable coupons adapted to contain the record of the various operations in said sequence.

25 In the handling of cotton and similar articles in bales and packages, it is desirable that each individual bale shall be so marked by the receiver that it can be readily identified and the shipper receive proper 30 credit therefor. It is further desirable that after the bale has been tagged, weighed, sampled and compressed that an additional tag be attached showing the result of these 35 various operations and indicating at a glance that they have been completed. It is also desirable that various records be kept, in separate offices, of these several operations. In order to obtain the above desired purposes, this invention contemplates the provision of a double ended tag, each end being 40 provided with means for fastening it to a bale, and a series of detachable coupons defined by lines of perforations arranged between the two ends of the tag.

45 Referring to the drawings:

Figure 1 is a plan view of the face of a tag constructed according to this invention, and

50 Figure 2 is a plan view of the reverse side of such a tag.

The tag comprises an elongated strip 10 of suitable material, such as cardboard, provided at either end thereof with an eyelet 11 which may be, if desired, supported by reinforcing washers 12, as is well known in the tag art. A tie wire 13, or other suitable

fastening means, is passed through each eyelet in order that either end of the tag may be attached to a bale. The strip 10 is divided into six detachable portions by lines of perforations 14, 15, 16, 17 and 18 so that the two end portions 19 and 20 may constitute individual tags when separated from the four coupons 21, 22, 23 and 24 contained between the inner ends of the tag portions 19 and 20.

Each portion of the strip contains an identifying index or number, such as 25, on the face thereof in a prominent position, and the two tag portions 19 and 20 have 70 these numbers duplicated on the back thereof. Each of the tags may have printed thereon the same of a consignee or any desired information, and may also include the shipper's name if desired, and in addition 75 to this, tag 19 contains nothing aside from the index number printed on both sides. Tag 20, however, has printed across the face and back thereof a broad stripe of any suitable color, for instance, blue, as shown at 26 80 in order that it may be readily recognized and differentiated from tag 19 when the two are separated from the coupons. This tag contains further a space designated "Flag number", in which space is adapted to be 85 placed a mark to indicate the quality of the material in the bale after it has been examined.

The two small coupons 21 and 22 each have printed thereon the legend "Cotton 90 sample coupon" and contain nothing in addition, except the index number 25.

The coupon 23 is divided into three spaces, that in the upper left hand corner having printed therein the index number 25; that 95 just below it having the legend "Weight" and adapted to have marked therein the weight of the bale after it has been determined by the consignee and the larger space on the right hand side of the coupon containing the legend "Flag number" and 100 adapted for the same purpose as the similar space on the tag 20. This coupon contains at the upper edge the legend "Lot sheet coupon".

105 Coupon 24 is substantially identical with coupon 23, but contains at the top the legend "Compress lot sheet coupon".

The tags constructed according to the above disclosure are used as follows by 110 a cooperative cotton growers' association:

When the cotton bales in their loosely

compressed state are received from the railroad by the association, each bale receives a tag such as shown in the drawing, the tags being printed in numerical series. The tag 5 is attached to the bale by the fastening means in the small tag 19 after which the bale is weighed and the weight thereof inserted in the two spaces provided on coupons 23 and 24.

- 10 The next operation is the sampling of the cotton in the bale. The bale is opened and a portion of the cotton removed as a sample. The main portion of the tag including all the coupons and the small tag 20 are detached 15 at the perforation 14 and taken with the sample to the grading room, leaving only the small tag 19 on the bale. In the grading room the cotton is inspected and given a "pool" number which designates the 20 grade and staple of the cotton. This "pool" number is inserted in the spaces headed "Flag number" on the coupons 23 and 24 and the small tag 20 and the two cotton sample coupons 21 and 22 are detached and 25 remain with the sample in order to identify it, by means of the index number, with the original bale.

In the meanwhile the bale has gone to the compress where it is further compressed 30 to the small compact bale suitable for storage or shipping by rail or water. When the "pool" numbers are stamped on the two coupons and the small tag 20, "Lot sheet 35 coupon" 23 is detached by the clerk marking the numbers and is filed at the office. Coupon 24 and tag 20 are then immediately attached to the same bale from which they were originally taken and the blue stripe or bar indicates to the compress or warehouse 40 man that the particular bale so marked is ready to be put in the warehouse or to be sold.

In case it is desired to ship this particular bale of cotton prior to the time it is put 45 in the warehouse, the shipping clerk makes a record thereof and as the bale goes into the car the "Compress lot sheet coupon" is detached so that the shipping clerk's record and the office record of the compress can 50 be compared to prevent any error. The compress in such cases have shipped the cotton bale before they have issued a warehouse receipt therefor so they immediately prepare such a receipt for that particular 55 bale and forward it to the office. However if the cotton is not shipped immediately but is put in storage in the warehouse, it is segregated in 100 bale lots all of the same 60 quality and as it is put in the warehouse the "Compress lot sheet coupons" are detached and when 100 such coupons are accumulated, a warehouse receipt is issued for the bales of cotton represented thereby and this 65 receipt may be used for collateral purposes if desired.

The various coupons attached and the records kept therewith and therefrom may be compared and checked by certain well known bookkeeping methods and it is not necessary for the purpose of this specification to further explain their use but it will be apparent that a highly desirable form of tag for the keeping of records is contemplated by this invention and while but one modification has been disclosed, it is desired 70 that the invention shall only be limited by the scope of the attached claims.

Having thus described our invention what we claim as new and desire to secure by Letters Patent is:

1. A device of the character described, comprising an elongated strip of material, means at each end of said strip whereby it may be fastened to a container, a line of perforations dividing said strip into two tags, corresponding identifying indicia on each tag, and a colored identifying stripe on one of said tags.

2. A device of the character described, comprising an elongated strip of material, means at each end of said strip whereby it may be fastened to a container, a line of perforations dividing said strip into two tags, corresponding identifying indicia on each tag, a colored identifying stripe on one of 90 said tags, and an appropriately designed space on said last mentioned tag to receive a quality mark.

3. An identification and record device for cotton bales comprising an elongated strip 100 of material, an eyelet at each end thereof, a fastening means in each eyelet, lines of perforations defining a tag at each end of said strip and a coupon between the inner ends of said tags.

4. An identification and record device for cotton bales comprising an elongated strip of material, an eyelet at each end thereof, a fastening means in each eyelet, lines of perforations defining a tag at each end of said 110 strip, and lines of perforations defining coupons between the inner ends of said tags.

5. An identification and record device for cotton bales comprising an elongated strip of material, an eyelet at each end thereof, a fastening means in each eyelet, lines of perforations defining a tag at each end of said strip, and lines of perforations defining coupons between the inner ends of said tags, and corresponding identifying indicia on 115 the tags and coupons.

6. An identification and record device for cotton bales comprising an elongated strip of material, an eyelet at each end thereof, a fastening means in each eyelet, lines of perforation defining a tag at each end of said strip, lines of perforations defining coupons between the inner ends of said tags, corresponding identifying indicia on the tags 125 and coupons, a designated space on one of 130

said coupons to receive the weight of the bale, and designated spaces on a coupon and a tag to receive a quality mark.

7. An identification and record device for
8 cotton bales comprising an elongated strip
of material, an eyelet in each end thereof, a
fastening means in each eyelet, lines of per-
forations defining a detachable tag at each
end of said strip, lines of perforations de-
10 fining detachable coupons between said tags,
corresponding identifying indicia printed

on each tag and coupon, a colored stripe on
one of said tags, a designated space on said
striped tag and on two of said coupons to
receive a quality mark, and designated 15
spaces on two of said coupons to receive
the weight of the bale to which the tags are
attached.

In testimony whereof we hereunto affix
our signatures.

JAMES LEONADUS RESPESS.
ARTHUR MAZYCK.
